CLAIM

The ornamental design for a receiver for dog training collar, as shown and described.

DESCRIPTION

FIG. 1 is a top front left perspective view of a receiver for dog training collar, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines showing portions of the article form no part of the claimed design.
